UNITED STATES PATENT OFFICE.

JAMES H. E. BRANSON, OF PHILADELPHIA, PENNSYLVANIA.

PASSENGER RAILWAY-CAR.

938,037.

Specification of Letters Patent. Patented Oct. 26, 1909.

Application filed April 21, 1909. Serial No. 491,264.

To all whom it may concern:

Be it known that I, JAMES H. E. BRANSON, a citizen of the United States, residing at the city of Philadelphia, in the county of Philadelphia and State of Pennsylvania, have invented certain new and useful Improvements in Passenger Railway-Cars, of which the following is a specification.

My invention has relation to means to facilitate safe entrance as well as exit to and from closable platform passenger cars, of the type which have become known, as pay-within-cars.

The principal objects of my invention are first, to provide the platform of a passenger railway car with twin doors opening outward, in unison, in different directions and closing inward, in unison, toward each other; second, to provide a passenger car on each side with twin doors opening outward in different directions and having on one side rails to be grasped by passengers on entering the car to safely mount a platform; third, to provide a passenger car with twin doors on each side opening outward, in unison, in two different directions and in opening, presenting hand gripping safety rails to entering or departing passengers; fourth, to provide a car with twin doors opening outward and closing inward toward each other and simultaneously lowering and raising a step and both operated by mechanism, controlled by a hand-lever from a motorman's station on the platform or a conductor's station at a point established between a platform and the main body of the car, which thereby provides entrance and exit ways to and from the said main car body with the platform of the car; fifth, to provide a passenger car having such defined operating doors provided with a hand-lever for operating a rod controlling mechanism connected with twin doors and a step adapted to be readily controlled from a motorman's station or a conductor's station to permit in the one instance and prevent in the other, the use of one set of doors on either side of the platform, as requirements may demand; and sixth, to provide a passenger car with twin doors swinging outward in different directions, and at the same time a step beneath, and both operating in unison by means controlled by a motorman or by a conductor from either of their respective stations, by means of a hand lever control-

ling the twin door and step operating mechanism located underneath the car and in such manner that but one or both sets of twin doors and a step or steps are operative at a time, and when operating only one set to provide one side of the platform for safe-guarding passengers on the platform in the event of leaning against closed doors thereof.

My invention stated in general terms, consists of a passenger railway car provided with twin platform doors arranged to be swung outward in unison, and simultaneously a step beneath to be brought into such relation with respect to the platform, as to permit of entrance or discharge of passengers to or from the platform and both the doors and step controlled by mechanism connected therewith, and arranged to operate in unison by manipulation of a hand-lever, either by a motorman on the platform or by a conductor at a point establishing entrance and exit ways to and from a platform with the main car-body.

My invention further consists of other features in such character of passenger railway car to be hereinafter fully described and claimed.

The nature, characteristic features and scope of my present invention will be more fully understood from the following description taken in connection with the accompanying drawings forming part hereof, in which—

Figure 1, is a longitudinal sectional plan, partly in elevation, of a passenger railway car, embodying main features of my said invention, showing the mechanical means for operating the twin doors and step by means operated by either a motorman from the platform or by a conductor between the platform and main car-body at a station established therein. Fig. 2, is a side elevational view of a passenger car, in broken section, showing the twin doors on one side of the platform closed and the step elevated, and also showing how in dotted lines the two doors connected with one another permit of a unison action and a step beneath, therewith; and further showing in dotted outline the passenger hand gripping rails, on the inner side of the respective doors. Fig. 3, is an enlarged, sectional plan view of the door and step operating mechanism of the car and in dotted outline the operating

hand-levers of said mechanism at respectively the motorman's station and at the conductor's station. Fig. 4, is a view in broken section, of the operating lever-rods of the door and step actuating mechanism and of the retracting springs thereof. Figs. 5 and 6, are views partly in section and partly in elevation of a step and the operating lever-arm of the same shown in broken section, the step in said views being illustrated in open and folded conditions. Figs. 7 and 8, are respectively, side and central sectional views through the standard with the hand grip head of the same and through which standard the door-and-step actuating-mechanism operating rods extend, controlled, by hinged handles from the said head for opening and closing either doors and step of a platform; and Fig. 9, is a top or plan view of the head of the standard of Figs. 7 and 8, showing the hinged handles in operative and inoperative positions.

Referring to the drawings 10, is a passenger railway car of the type well known as "pay-within-car", having a wide platform *a*, which merges into the main car-body *b*, having seats arranged longitudinally thereof, along the sides, as shown in Fig. 1. In this type of car is provided a wide space where the platform *a*, merges into the main car-body *b*, to provide a conductor's station *c*, arranged substantially midway of the said space and providing an entrance-way *a*¹, and an exitway *a*², on both sides of the said station *c*, as clearly illustrated in Fig. 1.

The platform on both sides are provided with twin hinged or pivotal doors *11*, *11*, closing toward each other and arranged so as to open outward, in unison, in opposite direction. The doors are preferably clipped to vertical rods *12*, *12*^a, extending through the platform *a*, and into sockets *12*^b, in the ceiling of the car framework. On the inside of the twin doors *11*, *11*, are provided hand gripping rails *d*, *d*^a, projecting preferably diagonally therefrom, for passengers to grasp, in entering or departing from a platform *a*, as indicated in dotted outline, in Fig. 2, and when the doors are swung outward, so as to occupy an open position.

13, is a pivoted folding step located below the doors on each side of the platform *a*, and suitably supported by means of brackets *14*, from the under framework *a*³, of the car, as illustrated in Figs. 5 and 6.

14^a, is a bumper centrally disposed from a bracket *14*^b, attached to the under framework *a*³, against which the rear portion of the step engages in an open position, as shown in Fig. 5, and which also serves to strengthen the step, while in an open position, in taking on or letting off passengers from a platform *a*, of the car 10.

15, is a centrally arranged metal strap or support extending from the underside of each

step 13, and which by preferably knuckle jointed links *15*^a, is connected to a cross-frame 16, consisting of end pivoted links *16*^a, *16*^b, rigidly connected respectively with the vertical door operating rods *12*, *12*^a, and pivoted with the cross-frame 16, as clearly shown in Fig. 3. The same mechanism, as described, is arranged on both sides with respect to the step and platform car doors and both are arranged so as to be operated in unison.

17, is an oblong hollow casing for containing operating parts or devices of the door and step actuating mechanism, which casing is made dish-shaped so as to contain a lubricating body, in which the said parts or devices are immersed to insure ease of movements thereof and to reduce as well friction on the several parts or devices in operation. From the cross-frames 16, on both sides of the said casing 17, containing the said parts or devices, secured to the underside of the platform framework, as shown, in Figs. 1 and 3, project rods *18*, *18*^a, extending through adjustable stuffing boxes or bearings *19*, *19*^a, Fig. 3. Each pair of rods *18*, *18*^a, is provided with a cam-surface cross bar 20, rigidly secured thereto and adapted to pass between guides 21, *21*^a, so as to direct the same by reason of their length, in their back and forth movements in the casing 17, in proper alining action for thereby insuring greater ease of movement of the said parts or devices, affected thereby. From the guides 21, projects an arm 22, carrying on both sides thereof buffers *e* and *e*^a, and in the wall of the casing 17, is also provided adjustable buffers *f* and *f*^a.

23, *23*^a, are pivoted lever-arms connected with brackets *g*, *g*^a, rigidly secured to the respective end walls of the casing 17, and carrying at the free end of the said lever-arms rollers *g*², *g*³, for respectively riding the outer edge of both of the cam-surface cross-bars 20, of the respective rods *18*, *18*^a, for operating the doors and step on each side by the cross-frame 16, with the pivoted link members *15*^a, *16*^a and *16*^b, thereof. The lever-arms 23, *23*^a, by means of pivotal links 24, *24*^a, are connected with a bell crank operated device 25, having at the free ends thereof rollers *25*^a, *25*^b, adapted to ride the inner edges of both of the cam-surface cross-bars 20.

26, *26*^a, are longitudinal operating rods, pivotally connected by means of links *26*^b, *26*^c, with vertical rods *27*, *27*^a, located either at the motorman's station *a*⁵, or conductor's station *c*, within standards *28*, *28*^a, and operated preferably by hinged hand levers *29*, *29*^a. The standards at both stations are provided with grip heads *30*, of the type as clearly shown in Figs. 7 and 8.

The respective longitudinal operating rods *26*, *26*^a, are connected by links *26*^d, *26*^e,

with the square shafts 31, of the bell crank device 25, for shifting the same as required, when the hinged operating lever 29 or 29^a, is operated, either at the motorman's station 5 ^{a⁵}, or a conductor's station ^c, of the car 10, as will be fully understood from Fig. 3, to open one pair of doors 11, 11, and to lower a step 13, beneath, by reason of being actuated in unison, by the hereinbefore described 10 mechanisms thereof. The bumpers ^f, in the folded position of the step on one side of the platform ^a of the car 10, and with the pair of doors 11, 11, closed to, as illustrated in Fig. 2, will be brought into contact with the pivoted lever-arm 23, and with the lower 15 arm of the bell crank device 25, in contact with the buffer ^{c¹}, and the opposite end of the bell crank device 25, in riding contact about midway in the length of the inner cam-surface edge of the cross-bar 20, and 20 at the same time, with the lever arm 23^a, in riding contact with the outer cam-surface edge of the opposite cross-bar 20, as clearly shown in Fig. 3, and further with the opposite side platform ^a, of the car of the pair of doors 11, 11, wide open, and likewise the step 13, beneath, as fully shown in said Fig. 25 3, of the drawings.

The links 26^b, 26^c, respectively, are provided with retracting coiled springs 32, 32^a, Fig. 4, from a post 33, for assisting in returning parts of the doors and a step actuating mechanism, to initial positions, that is, the position of the respective parts of 30 said mechanism as fully illustrated in Fig. 3.

It will be obvious that instead of operating the doors and steps in unison, by the connected operating mechanism, as described, at either a motorman's station ^{a⁵}, or a conductor's station ^c, by manipulating 40 a hand lever 29 or 29^a, adapted to detachably engage the vertical operating rods 27, 27^a, of the twin standards 28, 28^a, such may be actuated by well known air pressure cylinders of the types now used on cars. 45

The hereinbefore described invention, is not confined to manner of operating the twin doors and a step on a side of the platform ^a, in unison, in precisely the manner described, 50 nor is the present invention confined to the particular arrangement of the actuating mechanism for such doors and step, as hereinbefore explained; but

Having thus described my said invention, 55 what I claim as new and desire to secure by Letters Patent is:—

1. A passenger car provided with a platform merging into the main car-body and providing thereat a wide entrance-way, said 60 platform provided with double folding doors opening outward in different directions, a foldable step located beneath said platform on each side and mechanism for operating both, in unison, by the manipulating of a hand-lever either from the platform or the 65

entrance and exit ways located between said platform and main car-body, substantially as and for the purposes described.

2. In a passenger car, a platform provided with twin side doors adapted to fold inward 70 toward each other and outward in opposite directions from each other in unison, a step located beneath the platform and mechanism for operating both twin doors and step simultaneously and said doors on the inner 75 side provided with hand grips, substantially as and for the purposes described.

3. In a passenger car, a platform provided with infolding doors adapted to open in opposite directions in unison and having on one 80 side hand grips, a step and means controlled by a manual-device from within the car, for controlling the movements of the said doors and step, substantially as and for the purposes described. 85

4. A passenger car having a platform with twin infolding doors opening outward away from each other and provided in that position with devices to permit of safely mounting and alighting from a platform, a step 90 and means to actuate said doors and step in unison in opening and closing said doors, substantially as and for the purposes described.

5. In a passenger car, a platform provided 95 with infolding twin doors on both sides of said platform adapted to open in opposite directions in unison, and to close together, foldable steps located beneath said doors, means to actuate said doors and steps, said 100 means arranged to permit of the actuation of one set of said doors and a step, and to lock the other set of doors and step, from within the car, substantially as and for the purposes described. 105

6. In a passenger car, a platform provided with infolding twin side doors on both sides of said platform adapted to open and close in unison, a step beneath said doors, means for actuating both, simultaneously, said 110 means provided with a manual device for manipulating said means and arranged to readily operate one set of doors and step and the other set of doors and step so arranged as to be operated by either a motorman or 115 conductor, substantially as described.

7. In a passenger car having a platform provided with infolding twin doors, on each side, a folding step beneath said doors, mechanism connected with both of said twin doors 120 and step to permit of the operating of both sets of side twin doors and step in unison either from a motorman's station or a conductor's station or conjointly from both stations within the car, substantially as and for 125 the purposes described.

8. In a passenger car having a platform provided with twin doors opening in opposite directions, a step opening outward, mechanism connected with said twin doors and 130

step for simultaneously actuating both doors and step, said mechanism having operating devices adapted to be brought in operative position by either a motorman or a conductor to effect a unison of action of both twin doors and a step from either side of said platform at the same time, substantially as and for the purposes described.

9. A passenger car, having a main car body provided with an end platform having infolding twin side doors adapted to open outward in opposite directions in unison,

a foldable step located beneath said doors, and means for actuating said doors and step and said means controlled by devices within the car, substantially as and for the purposes described.

In witness whereof, I have hereunto set my signature in the presence of two subscribing witnesses.

JAMES H. E. BRANSON.
